UNITED STATES PATENT OFFICE.

WILLIAM BRUCE, OF BEMENT, ILLINOIS, ASSIGNOR OF ONE-HALF TO IRA C. WALLS, OF SAME PLACE.

DESIGN FOR A WAGON-BED STANDARD.

SPECIFICATION forming part of Design No. 82,660, dated May 15, 1900.

Application filed April 20, 1900. Serial No. 13,688. Term of patent 7 years.

To all whom it may concern:

Be it known that I, WILLIAM BRUCE, of Bement, in the county of Piatt and State of Illinois, have invented and produced a Design 5 for a Wagon-Bed Standard, of which the following is a specification.

In the drawings forming part of this specification, Figure 1 is a side elevation of a standard shaped in accordance with my design. 10 Fig. 2 is a face elevation of the standard. Fig. 3 is a back elevation, and Fig. 4 is a plan.

The essential characteristics of the design are a foot or base 1, a standard composed of 15 a rib 2 and a rib 3 at right angles with rib 2, and lugs 4, extending downward from the base. The base is flat on its under surface. One of its ends and two of its sides are defined by right lines describing right angles, 20 and its other end, 1^a, forms a reduced nose, the sides of which approximate arcs of circles concavely disposed. Rib 2 rises from the straight end of the base. It is diminished in width by curved lines for a short 25 distance as it rises. Its defining-lines are parallel throughout the greater portion of its length, and its top is rounded off. The rib

3 conjoins at one edge with the center of rib 2. Its upper corner is rounded off. Its outer line is straight and slightly divergent from the rib 2 to near the base, whence it spreads out in gradual curves both sidewise and outward, as shown at 3^a. Circular bosses are formed on opposite sides of the rib 3 of the standard, and the axes of opposing bosses 30 are coincident. The lugs 4 extend downward from the straight portions of the sides of the base. They are parallel one with the other and both with a continuation of rib 3. The rear edges of the lugs are straight and flush 35 with the inner surface of rib 2, while the front edges describe convex curves. 40

Having described my invention, what I claim as new, and desire to secure by Letters Patent, is—

The design for a wagon-bed standard, as herein shown and described.

In testimony whereof I sign my name in the presence of two subscribing witnesses.

WM. BRUCE.
